GOLF CLUB

Herbert S. Petry, Brooklyn, N. Y.

Application September 12, 1931, Serial No. 562,469

3 Claims. (Cl. 273—80)

This invention relates to improvements in golf clubs.

An object of the invention is to provide an improved golf club with an easily flexed or whippy shaft of the character hereinafter indicated for use as an instruction club and so designed as to aid the user in acquiring a proper swing.

Another object of the invention is to provide a golf club for general play with an easily flexed or whippy shaft so designed that when the club is properly swung, the club-head will travel approximately along the line of flight of the ball during the period of impact.

A further object of the invention is to provide a golf club having a shaft so designed that it may be readily bent or flexed in one direction while rigidly resisting bending in a direction at right angles thereto.

A further object of the invention is to provide a golf club with a shaft having all the advantages inherent in a readily flexed or whippy shaft, but designed to resist bending during the moment of impact, except substantially along the line of flight of the ball.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Fig. 1 is an elevational view of a golf club embodying the invention;

Fig. 2 is a sectional view along the lines 2—2 of Fig. 1;

Fig. 3 is a sectional view along the lines 3—3 of Fig. 1;

Fig. 4 is a sectional view along the lines 4—4 of Fig. 1; and

Fig. 5 is an enlarged view of the club-head and the portion of the shaft immediately adjacent thereto.

In golf instruction, and in the playing of the game itself, it is essential that the pupil or player have the "feel" of the club. Golf instructors have quite generally advised their pupils to handle the clubs and particularly the wooden clubs as though the shaft had no weight or as though the club head were a stone on the end of a string.

The pupil is told to delay the wrist action incident to striking the ball until the hands have reached almost the lowest portion of the arc of the swing, when the wrists are to be "uncocked" and the club-head snapped through the ball. 60 These and similar instructions have for their object the perfection of a smooth golf swing which applies the maximum hitting force to the club-head at the moment of impact.

It has frequently been found that the proper 65 swing can most readily be acquired and the true snap most readily imparted to the club head at the moment of impact when a shaft with a good deal of resiliency or whip is employed. Under those circumstances, the club head more nearly 70 approximates the condition of a stone on the end of a string. However, when an easily flexed or whippy shaft is used, it is found that unless the swing is absolutely correct, the club head tends to turn at or before the moment of impact. 75 When the club head turns, a slice or hook is imparted to the ball.

I have found that if a shaft is employed which permits the club head to be snapped or whipped only along one properly positioned axis, the club 80 will retain the advantages of "feel" normally possessed by clubs with whippy shafts, and will at the same time possess the advantages of rigidity and non-turning of the club head, which the club with the ordinary whippy shaft lacks. 85

In the embodiment of the invention shown, 10 represents a golf club provided with a head 11, a shaft 12 and a grip 13. The shaft is preferably so designed as to be readily bent in one direction, while resisting bending in a direction at an angle 90 of 90 degrees thereto. This is accomplished in the embodiment of the invention shown by cutting away or flattening a portion of the shaft so that the diameter of the shaft in one plane is gradually and substantially decreased from a 95 point near the grip to a point near the club head, while the diameter of the shaft in a plane at an angle of 90° thereto, remains, except for the normal taper of the shaft, substantially constant. The rigidity of the shaft in a plane through the 100 long axis of a cross-section thereof will approximate that of a circular shaft of equal diameter while a whippy tendency will be imparted to the shaft in a plane passing through the short axis of a cross-section thereof. 105

I have found that when a shaft so designed is mounted in a club head with the long axis of the cross-section of the shaft in a plane passing perpendicularly through the shaft when the club head is soled on the ground, the rigidity imparted 110

to the shaft by the construction described has little or no effect in preventing the club head from turning during impact with the ball. When, however, the shaft is so mounted that the long 5 axis of the cross-section is inclined at an angle of approximately 45 degrees to a vertical plane passing through the shaft when the club is soled, as shown for example in Fig. 5, the club head no longer turns upon impact, but is snapped or driven 10 against the ball in such a manner that its striking surface remains in a proper position throughout the impact.

With the improved shaft mounted in the club head as shown in Fig. 5, that is with the long 15 axis of the shaft rotated counter-clockwise an angle of approximately 45 degrees from a vertical plane passing through the shaft, the snap imparted to the club head when the shaft is properly swung is of such a nature as to cause the club 20 head to strike downwardly into the ball. This results in a substantial decrease in the number of topped shots and is of substantial aid in securing uniformly well hit shots.

Where the club is to be used for instruction 25 purposes, the shaft is preferably made excessively whippy, so that the club head will be given an excessive snap at the moment of impact. With a club so constructed, the pupil acquires very quickly the certain "feel" of the club head which is 30 so greatly desired. Quick, jerky back swings cause the club head to sway about the shaft to the great discomfort of the pupil who quickly learns to make the back swing slow and steady.

I have found that with the shaft positioned in 35 the head as has been described above, the golf club must be properly held at the top of the back swing, or the club head will dip and sway in an awkward and uncomfortable manner. With an excessively whippy shaft positioned in the club 40 head as described above, the club head must be properly swung against the ball, for if the pupil's wrists are brought into play at too early a point in the down swing, or if the snap of the wrists is delayed too long, an exaggerated hook or slice 45 is the result and the pupil is immediately aware that he has swung improperly by the action of the club head on the shaft.

I have found that by swinging a club embodying 50 my invention, a pupil acquires the proper swing and the proper wrist action in a relatively short time, for until he does so, the action of the club head and the shaft makes the swing noticeably uncomfortable.

Where the golf clubs are intended for use in 55 playing the game, the shaft should be so constructed as to render some appreciable resistance to flexing in every direction, that is, the shaft should not be as whippy through its narrow cross section in a club designed for use on the links, as in a club intended for practice and instruction.

60 In the embodiment of the invention shown, I have illustrated at 13, a club grip of a patented type known to the trade as the "Progrip". I have

found that such a grip may be used in connection with my improved golf club with highly satisfactory results, when the grip is so positioned that the bearing surface for the left thumb, shown in Fig. 1 at 14, is positioned parallel to the long 80 axis of the cut-away shaft so that the driving force imparted by the left thumb is directed at right angles to that axis. With a "Progrip" in such position, the pupil or player tends to grasp the club correctly and to hold it in such a way that the long axis of the cross section of the shaft is properly positioned and the club head properly driven against the ball.

While I have described a shaft made of wood with portions cut away to give a whippy action to the shaft in one plane, it is to be understood that steel shafts may be used as well and that any device may be employed to weaken the shaft along one plane while retaining its rigidity in another plane.

90 Since certain changes may be made in the above article and different embodiments of the invention could be made without departing from the scope thereof, it is intended that all matter contained in the above description or shown 95 in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

110 1. A golf club of the character described, having a shaft more easily bent in one plane than in any other, the shaft being so mounted in the club head that the plane along which it may be most easily bent is at an angle of approximately 45° in a clockwise direction to a vertical plane 115 passing through the shaft when the club head is placed normally on the ground.

120 2. A golf club of the character described, having a shaft adapted to rigidly resist bending in one plane and to bend freely in a plane at right angles thereto, the shaft being mounted in the club head in such a way that its plane of greatest rigidity is at an angle of approximately 45° in a counter-clockwise direction to a plane passing 125 vertically through the shaft when the club head is placed normally on the ground.

130 3. A golf club of the character described, having a wooden shaft of roughly elliptical cross section so mounted in the club head that the long axis of the cross section of the shaft is at an angle of approximately 45° in a counter-clockwise direction to a plane passing vertically through the shaft when the club head is placed normally on the ground.

135 HERBERT S. PETRY.
